UNITED STATES PATENT OFFICE.

ELMER R. CORWIN, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONE EXCHANGE SYSTEM.

1,109,163.

Specification of Letters Patent.

Patented Sept. 1, 1914.

Application filed August 10, 1912. Serial No. 714,416.

To all whom it may concern:

Be it known that I, ELMER R. CORWIN, citizen of the United States, residing at Chicago, in the county of Cook and State of Illinois, have invented a certain new and useful Improvement in Telephone Exchange Systems, of which the following is a full, clear, concise, and exact description, reference being had to the accompanying drawings, forming a part of this specification.

My invention relates to those telephone exchange systems in which electro-magnetic mechanism is employed for extending telephone lines and while my invention has been specifically embodied in a system in which the operators have control of such electro-magnetic mechanism yet the invention is not to be restricted to such a system.

In accordance with my invention I provide a telephone exchange system which includes telephone lines, such for example as those which extend from subscribers' stations to an exchange through the invention is not to be limited to subscribers' telephone lines, extensions for such telephone lines, a line extending connecting device, controlling circuits associated with different telephone line extensions for governing the association of said connecting device, and operator controlled means for changing the character of the controlling circuits.

My invention, in another of its aspects, may generally be described as a telephone system including telephone lines extending from stations to an exchange, extensions for such telephone lines having contacts at the exchange, a line extending connecting device for engagement with the contacts, controlling circuits for governing the association of said connecting device, each controlling circuit having a contact for engagement with the connecting device, the controlling circuits being associated with different telephone line extensions, means for changing the character of the controlling circuits associated with desired telephone line extensions, and means for maintaining the connecting device in association with a modified controlling circuit.

In the preferred way of practising my invention each telephone line that is to be extended is connected with a set of contacts which may be in the form of traveling wipers, the waiting contacts of which are

divided into sets each individual to a telephone line extension. Each of these sets of waiting contacts includes a contact that is contained in a controlling circuit individual thereto. Each of these controlling circuits, as I have embodied my invention in one form, has a manually controlled switching device individual thereto for controlling its character. The group of wipers now individual to the line that is to be extended rotates until one of the wipers of such group engages a contact of a controlling circuit whose character has been temporarily modified for the purpose of causing the arrest of the wipers, this particular waiting contact and the wiper engaging the same establishing or otherwise modifying the altered controlling circuit to arrest the wipers. The wipers of the arrested group that are companion to the wiper engaging the waiting contact of the altered controlling circuit themselves engage contacts that are terminals of the selected talking extension. This particular extension which has been added to a telephone line may extend directly to a subscriber's station if the telephone system is of a sufficiently small number of lines or it may extend to another group of wipers which may be similarly connected with another telephone line extension, and so on, whereby the system may be adapted to any number of lines.

I will explain my invention more fully by reference to the accompanying drawings showing the preferred embodiment thereof and in which—

Figure 1 is a very simple diagram generally outlining important features of the invention; Fig. 2 is a general diagrammatic view drawn along the lines of Fig. 1 but in which the invention is adapted to a larger system; Fig. 3 is a diagram that is intended to be somewhat general but which is more specific than the diagram of Fig. 1; Figs. 4 and 5, taken collectively with the conductors at the top margins thereof in alinement, illustrate one embodiment of the invention more in detail; and Fig. 6 shows a detail of construction.

Like parts are indicated by similar characters of reference throughout the different figures.

Referring first to Fig. 1, I have there illustrated telephone stations 1, 2, 3 and A by means of circles. Telephone station A is illus-

trated as having its line manually extended by an operator by means of a plug and jack at 4, the link connector connected with the plug 4 terminating in talking wipers illustrated by the single wiper 5. I have shown the manual extension of the line from station A to the wiper 5 merely to simplify the illustration, though of course such telephone line could be extended in the manner described as in toll line service. The talking wiper 5 has an associate wiper 6 that constitutes a terminal common to a plurality of controlling circuits 7, 8 and 9. A conductor which is common to these controlling circuits, and of which conductor the wiper 6 is a terminal, includes a wiper arresting magnet 10, a battery 11 common to the controlling circuits, and keys 12, 13 and 14, the key 14 having a normal contact by which the key 13 is connected with the battery 11 and the key 13 having a normal contact by which the key 12 is connected with such battery. The alternate contacts of keys 12, 13 and 14 are respectively individual to the controlling circuits 7, 8 and 9. The controlling circuit 7 pertains to the line extending from station 1, the controlling circuit 8 pertains to the line extension from the station No. 2, and the controlling circuit 9 pertains to the line extending from the station No. 3. The controlling circuits contain electro-magnets 15, 16 and 17 individual to the lines 1, 2 and 3, these magnets being operated when the lines to which they are individual are to become connected with telephone lines that are to be extended into connection therewith, these magnets serving to arrest the connecting device 5, 6 in association with contacts 18 that pertain to desired telephone line extensions and the controlling circuits associated therewith. The circuits 7, 8 and 9 include waiting contacts that are individual thereto and which are designed to be engaged by the wiper 6. These waiting contacts are provided each with an associate contact or set of contacts that are individual to the subscribers' telephone lines or telephone line portions, such as trunk lines, that are to become connected with the line which is to be extended. All of these waiting contacts are designated by the numeral 18 in Fig. 1. Assuming that a calling line (A) has in some way become connected with the wiper 5 and has informed a receiving operator that he desires connection with station No. 1. The operator will depress the key 12 so as to charge the waiting contact individual to the circuit 7. The wiper rotating device 19, which has been set into operation by some suitable means, is caused to turn the wipers until the wiper 6 engages the waiting contact individual to the controlling circuit 7 whereupon circuit through the wiper arresting magnet 10 will be closed to arrest the wiper 6 in engage-

ment with its then engaged waiting contact, in which engagement the wiper 5 is connected with the line leading to station 1. Similarly, if station 2 is to be connected with station A the key 13 will be depressed, whereupon wipers 5 and 6 will become connected with the middle group of contacts at 18. If station A is to be connected with station 3, the key 14 will be depressed, whereupon the wipers 5 and 6 will become connected with the third group of waiting contacts at 18. The keys 12, 13 and 14 in addition to charging the waiting contacts individual thereto also charge the wiper 6 common to the controlling circuits with current of opposite polarity so that circuit is established when a charged waiting contact is engaged by the charged wiper. While the line to be extended is shown as being provided with traveling wipers and the line extensions are shown as being provided with waiting stationary contacts, I do not wish to be limited to terminals for the line to be extended and co-operating stationary terminals for the line extensions.

As is understood, the telephone line extension which is to be added to another telephone line may be in the nature of trunk lines or link connectors, or may themselves be telephone lines that extend to subscribers' stations. In an exchange larger than that for which the system in Fig. 1 is adapted the telephone lines would be divided into groups, each group of telephone lines having terminal waiting contacts in a switch, one group of such telephone lines being indicated at the right in Fig. 2 with its waiting contacts indicated at 20, each of the groups of such telephone lines being connected with waiting contacts similar to those indicated at 20. Each switch having waiting contacts 20 is provided with traveling wipers indicated at 21, these wipers constituting a line extending connecting device for connection with one of the lines of the group to which it pertains. The sets of wipers 21 pertaining to the different groups of subscribers' telephone lines are to be selected according to the group in which the desired line is included, these wipers being connected by means of telephone line extensions 22 with waiting contacts illustrated at 23, each set of waiting contacts at 23 being connected with a set of wipers 21. The waiting contacts at 23 are associated with wipers indicated at 24, these latter wipers being employed for associating one of the telephone line extensions 25 with a selected telephone line extension 22. There are a plurality of sets of wipers 24 each in association with a different group of waiting contacts 23 and these wipers 24 are connected through the telephone line extensions 25 with waiting contacts illustrated at 26, each set of waiting contacts at 26 being connected with a diff. 183

ferent set of wipers 24. The waiting contacts 26 are associated with wipers indicated at 27, the wipers 27 being adapted to become connected with a selected one of several telephone line extensions 25 extending to the desired set of wipers 24. The wipers 27 are connected, for example, with calling station A by way of the cord and plug illustrated at 4, though other means may be employed for associating the wipers 27 with the calling line. Thus by means of my invention the wipers 27 are connected with one of several telephone line extensions 25 that has the wipers 24 that are associated with a particular set of waiting contacts 23 that has the desired telephone line extension 22 which is provided with wipers 21 that are associated with the waiting contacts 20 among which are included those waiting contacts 20 that are terminals of the desired subscriber's line. When a subscriber initiates a connection in any suitable way and assuming that the system is presided over by operators, the operator will proceed to extend the calling line into connection with the desired line by the following operations: The key 28 individual to the desired telephone line extension and the associate controlling circuit (there being as many keys 28 and controlling circuits to which they pertain as there are such telephone line extensions 25 and each of which keys 28 may be multiplied at different operators' positions) is depressed partially to establish a circuit including the battery 11, the key 28 and its alternate contact, the closed switch 29, a waiting contact at 26 which is in association with the waiting contacts of the selected telephone line extension 25, the wiper 30, and the wiper arresting magnet 31. When the wiper 30 engages the waiting contact connected with the switch 29, circuit is closed through the magnet 31 to arrest the wipers whereby the calling telephone line is extended into connection with the desired telephone line extension 25. By equipment to be described in connection with another figure, the motor device 32 is set into operation when the selected telephone line extension 25 has been connected whereby switch 29 is opened to protect the circuit previously established at 28 so that contacts 26 of other switches which are similarly connected with other keys 28 and which contacts of these switches are in multiple relation with the contacts 26 shown, will not have their circuits partially established. The operator will depress the key 33 individual to the desired telephone line extension 22 and the associate controlling circuit (there being as many keys 33 and controlling circuits to which they pertain as there are such telephone line extensions 22 and each of which keys 33 may be multiplied at different operators' positions) to partially establish a circuit including the battery 11, the key 28 and its normal contact, the key 33 and its alternate contact, the closed switch 34, a waiting contact at 23 which is in association with the waiting contacts of the selected telephone line extension 22, the wiper 35, and the wiper arresting magnet 36. When the wiper 35 engages the waiting contact connected with the switch 34 circuit is closed through the wiper 30, the contact engaged thereby, magnet 31 and the magnet 36 to arrest these wipers whereby the calling telephone line is extended into connection with the desired telephone line extension 22. By equipment to be described in connection with another figure, the motor device 37 is set into operation when the selected telephone line extension 22 has been connected whereby switch 34 is opened to protect the circuit previously established at 33 so that contacts 23 of other switches which are similarly connected with other keys 33 and which contacts of these switches are in multiple relation with the contacts 23 shown, will not have their circuits partially established. The operator will also depress one of the keys 12, 13, 14 belonging to the controlling circuit individual to the telephone line extending to the wanted station, 1, 2, or 3 (there being as many such keys and controlling circuits to which they pertain as there are such telephone lines having waiting contacts at 20, that is there are as many keys 12, 13, 14 as there are telephone lines in a group, and each of which keys 12, 13, 14 may be multiplied at different operators' positions) partially to establish a circuit including the battery 11, keys 28 and 33 and their normal contacts, the depressed key 12, 13 or 14 and its alternate contact, the closed switch at 15, 16 or 17 according to the line selected, the waiting contacts at 20 which are in association with the desired subscriber's telephone line, the wiper 38 and the wiper arresting magnet 39. When the wiper 38 engages the waiting contact connected with the switch at 15, 16 or 17, circuit is closed through the magnet at 15, 16 or 17 (by way of wipers 35 and 30 and magnets 36, 31) to arrest wipers 38, 21 whereby the calling telephone line is extended into connection with the desired subscriber's line.

Fig. 3 is furnished to show more of the circuit connections that were omitted from Fig. 2 for the sake of clearness. The system shown in Fig. 3 illustrates how a calling line may secure access to each of the other nine hundred ninety-nine lines of a thousand line system, enough apparatus being suggested in Fig. 3 to accomplish this result. However the equipment suggested in Fig. 3 is not sufficient to take care of the traffic in a thousand line exchange and it is therefore understood that the waiting contacts 26 of one switch shown are in multiple relation with

similar contacts 26 of other switches having wipers 27, 30 employed by other subscribers' lines, there being say one hundred switches having the contacts 26; that the waiting contacts 23 of each selector switch are in multiple relation with similar waiting contacts of say two other selector switches having wipers 24, 35; and that the waiting contacts 20 of each connector switch are in multiple relation with similar waiting contacts of say nine other connector switches having wipers 21, 38, the numbers of the switches varying according to the traffic requirements. Only one extension 25 is indicated as extending from waiting contacts 26, although the elements 29, 32, 35 and 36 individually associated with other telephone line extensions 25 are illustrated, and only one extension 22 is indicated as extending from waiting contacts 23, although the elements 34, 37, 38 and 39 individually associated with other telephone line extensions 22 are illustrated. Each of the telephone line extensions 22 reaches a connector switch having the waiting contacts 20, each connector switch having ten subscribers' lines (1, 2, 3, etc.) terminating in the waiting contacts 20 and also having waiting contacts that are in circuit with magnets 15, 16, 17, etc. Where there are three connector switches to each group of multiply connected connector switches ten subscribers' lines are in connection with the waiting contacts of each such switch. Each of the operators has a set of ten keys 28, the contacts of these keys 28 among the different operators' positions being multiplied so that each operator may have access to any of the switches having contacts 26 and to said contacts 26. Each of the operators has a set of ten keys 33, the contacts of these keys 33 among different operators' positions being multiplied so that each operator may have access to any of the switches having contacts 23 and to said contacts 23. Each of the operators has a set of ten keys 12, 13, 14, etc., the contacts of these keys 12, 13, 14, among different operators' positions being multiplied so that each operator may have access to any of the switches having contacts 20 and to said contacts 20. Where the exchange exceeds 1,000 lines, additional connector switches will be required and it will be readily understood by those skilled in the art how an exchange in excess of 1,000 lines may be equipped by the interposition of other selector switches in advance of the connector switches, such additional selector switches of course requiring associate buttons having functions similar to the buttons 33. The thousand line system which has been taken for an example will be sufficient to enable my invention to be understood.

Reference will now be had to Figs. 4 and 5 which amplify the circuit arrangement

shown in Fig. 3. Assuming that subscriber's station No. 1 desires communication with subscriber's station No. 2, the calling subscriber will remove his telephone receiver 40 from its switch hook 41 to open the bridge containing the signal bell 42 and condenser 43 and to close the metallically continuous bridge containing the telephone transmitter 44 and the telephone receiver 40. Circuit is thereupon established through the relay 45 which may be traced from the grounded terminal of this relay through its winding, the upper armature switch of ringing relay 46 and its normal contact (this relay being operated only when its line is a called line), the sides of the calling line, the lower armature switch of relay 46, and its normal contact, next to the uppermost armature switch of relay 15 and its contact, the relay 47, to the grounded battery 48, the battery 48 also supplying talking current to the transmitters. The relay 47 may be common to the lines of a group of subscribers' lines and when its armature is attracted a circuit is established which is traceable from the grounded battery 48 through the circuit interrupter 49, the armature of relay 47 and its contact, the lowermost armature switch of relay 50 and its normal contact, the motor magnet 51, to ground. The circuit of the motor magnet 51 is interrupted so that its armature moves the ratchet wheel 52 that carries wipers 53, 54, 55, 56 and 57 that pass over sets of waiting contacts belonging to the group of telephone lines having the relay 47, there being two sets of such waiting contacts indicated at 58, 59, 60, 61 and 62. When a subscriber initiates a call a circuit connection is established for the waiting contact 62 belonging to his line which circuit connection may be traced from the contact 62 of the calling line, the lowermost armature switch of relay 45 and its then engaged contact, the follow-up contact of the armature switch immediately above the core of relay 15, the upper winding of the relay 15, to the grounded battery 48. That is potential is placed upon the waiting contact 62 of a calling line by connecting the grounded battery 48 therewith, the contacts 62 of non-calling lines being clear of such potential. When the wiper 57 engages the contact 62 having this potential the circuit connection just traced has a continuation that establishes a closed circuit which continuation includes the wiper 57, the follow-up normal contact of the upper armature switch of relay 50, the winding of relay 50, the upper armature switch of relay 63 and one of its contacts, to ground. Thus the magnet 50 becomes energized and its upper armature switch leaves its normal follow-up contact into engagement with its alternate contact

to establish a locking circuit through the magnet 50 and at the same time the lower armature switch of relay 50 is removed from its normal contact into engagement 5 with its alternate contact to open the circuit of motor magnet 51 whereby the wipers upon the actuated ratchet wheel 52 (the wipers 53 to 57 inclusive) are arrested. The locking circuit established by the magnet 50 may be traced from the grounded 10 battery 48, the upper winding of relay 15, (the armature switch immediately above the core of this relay having left its normal follow-up contact and now engaging its alternate contact to the circuit initially 15 established for this relay 15 at the lowermost armature switch of the previously energized relay 45), the armature switch immediately above the core of relay 15, the 20 alternate contact of this armature switch, the waiting contact 59 of the operated wipers, the wiper 54 engaging this waiting contact, the upper armature switch of relay 50 and its alternate contact, the winding of 25 this relay 50, the upper armature switch of relay 63 and one of its normal contacts, to ground. The locking circuit for the upper winding of relay 15 continues through its armature switch immediately above its 30 core, the alternate contact of this armature switch, both sides of the calling subscriber's line, the relay 45, to ground.

One side of each telephone line is permanently connected with the talking waiting 35 contact 59 and the other side of each subscriber's line is connected with the talking waiting contact 58 when the upper armature switch of relay 45 is attracted. Thus the talking waiting contacts 58 and 40 59 are connected with the talking wipers 53 and 54 respectively, whereby the operators' telephone conductors 64 are connected with the calling subscriber's line to include the operator's telephone set 65 in circuit 45 with the calling subscriber's line. The operator is now in telephonic communication with the calling subscriber, this feature of the invention being covered by my application Serial No. 503,345, filed June 21, 1909, 50 though it is to be understood that in practising my invention I do not limit myself to the manner in which communication is established between calling subscribers and the operators. When the operator has received the number of the desired line she 55 actuates the buttons or switches that pertain to the waiting contacts of the desired line, the waiting contacts extending to the wipers 21, 38 of the connector switch of the desired 60 line, the waiting contacts pertaining to the selected telephone extension 22, and the waiting contacts pertaining to the selected telephone extension 25, these buttons being illustrated at the right of Fig. 5, and there- 65 after depresses the button or switch 66.

Two sets of such buttons are shown and two operators' telephone sets 65 are shown, these elements being located at two operators' positions. When the selected buttons 28, 33, 12, 13 or 14 are initially depressed they are 70 not then immediately effective, the circuits controlled by these buttons being open at the lowermost armature switch of relay 63. The button 66 has a plunger in which there is a notch 67, this notch being normally out 75 of line with the nose of the armature of relay 68. When the button 66 is depressed its notch 67 is brought into register with the nose of the armature of relay 68 so that this armature then engages a grounded contact to establish a circuit which is traceable from this grounded contact through the armature of magnet 68, and the winding of magnet 50 whereby a ground for magnet 50 replaces the ground previously 80 provided for this magnet at the upper armature switch of relay 63 and which latter ground is later removed when the magnet 63 is energized. When the key 66 is depressed it moves the switch members 69 85 and 70 into engagement with their contacts, the switch 70 closing a circuit which may be traced from the grounded armature switch of relay 63, the contact connected with the switch member 70, the contact engaged by the switch member 70, the actuated wiper 56, the waiting contact 61 engaging this wiper, the lowermost armature switch 90 of relay 15 and its previously engaged contact, the lowermost armature switch of relay 71 and its normal contact, the motor magnet 62, the interrupter 49, to the grounded battery 48. The motor magnet 62 due to the interrupter 49 operates the ratchet wheel 72 to cause the wipers 73, 100 74, 75 carried by the ratchet wheel 72 to travel until these wipers engage waiting contacts 76, 77, 78 that are free for engagement, such contacts being free for engagement when the contacts 78 thereof are connected with the ground at the relay 63, there being one such relay for each operator's position and such connection being effected when a calling subscriber is connected 105 with an operator in a manner previously 110 described. The grounded battery 48 is connected with the wiper 75 by way of the switch 79 which is closed upon the initial movement of the ratchet wheel 72, the winding of relay 71, the upper armature switch 115 of this relay, and the normal follow-up contact of this armature switch so that when the wiper 75 engages the contact 78 the magnet 71 is energized to establish a locking circuit for itself which continues 120 through its upper armature switch and its alternate contact, the actuated wiper 74, the contact 77 engaged thereby, one side of the calling line, the calling substation, the other side of the calling line, to the ground at 125 130.

the relay 45. When battery was connected with the wiper 75 through the normal follow-up contact of the upper armature switch of relay 71, current from battery found passage from the wiper 75 through the contact 78, the employed waiting contact 60, the actuated wiper 55, the intermediate armature switch of relay 63 and its normal follow-up contact, the winding of relay 63, to ground. The relay 63 is now energized and establishes a locking circuit for itself which is traceable from the grounded coil of relay 63, the alternate contact of its intermediate armature switch, the switch element 69 and its contact, to the grounded battery 48. Ground is now removed from the employed contact 78 so that the wipers 73, 74, 75 of any other switch cannot rest upon any waiting contacts in multiple with the contacts 76, 77, 78 of which contact 78 is grounded, it being understood that the waiting contacts 76, 77, 78 have multiplied counterparts in switches having wipers similar to 73, 74 and 75. The removal of ground consequent upon the attraction of the upper armature switch of relay 63 has opened the circuit of the motor magnet 62 so that this motor magnet ceases to work and allows its wipers to remain in engagement with the automatically selected waiting contacts. Only two switches having the wipers 73, etc., are shown and the lowermost switch is caused to operate first if the other switch is idle owing to the fact that the motor magnet 62 of the upper switch depends partially for its circuit upon the engagement of the lowermost armature switch of the lower relay 71 with its alternate contact. If there were more switches with motor magnets 62 the switches would be permitted to operate in succession by means of the lowermost armature switches of relays 71 introduced therebetween. The talking wipers 73 and 74 and the additional wiper 75 are respectively connected with the two talking wipers 27 and the extra wiper 30, which latter wipers are now brought into connection with the waiting contacts 26 as a consequence of the establishment of a circuit which may be traced from the grounded battery 48, the interrupter 49, the motor magnet 79, the lowermost armature switch of relay 31 and its then engaged contact, the waiting contact 76 engaged thereby, to the grounded relay 45 by way of its upper armature switch. The armature of magnet 79 operates a ratchet wheel 80 that carries wipers 27, 30 and this ratchet wheel continues to rotate until the rotating wiper 30 engages a waiting contact at 26 complementary thereto and which complementary waiting contact at 26 has battery placed thereupon by a path traceable from the lower pole of the bat- tery 11, the winding of trip magnet 81 common to buttons 28 at an operator's position, the serially related switches that include the bell crank contact levers 82 pivoted at their lower ends to the particular switch 28, in this instance the uppermost switch, the contacts 83 of the depressed switch 28, the switch 29 and its normal contact, to the waiting contact 26 complementary to the wiper 30. Circuit is closed when the employed wiper 30 engages the contact 26 thus connected with battery 11 owing to the fact that the wiper 30 is connected with the upper terminal of the battery 11 by a path which may be traced from the upper terminal of this battery, the lowermost actuated armature switch of relay 63 and its contact, the actuated wiper 55, the waiting contact 60 engaging the same, the employed waiting contact 78 and the actuated wiper 75 engaging the same, the switch 84 closed upon the initial operation of the ratchet 80, the upper winding of relay 31, to the aforesaid wiper 30. The upper coil of relay 31 thus becomes energized to arrest the wipers by opening the circuit of the motor magnet 79 at the lowermost armature switch of relay 31. The relay 31 is provided with a lower winding that serves to maintain the energization of the relay core, the circuit being traced from the grounded battery 48, the lower winding of relay 31, the upper armature switch of relay 31 and its previously engaged contact, the actuated wiper 74 and the waiting contact 77 engaged thereby, both sides of the calling line, to the grounded relay 45. The talking wipers 27 are now connected with a selected line extension 25. This line extension 25 terminates in talking wipers 24 and an extra wiper 35, such line extension being prevented from selection by any other wipers 27, 30 owing to the fact that battery 11 is disconnected from the waiting contact 26 engaged by the arrested wiper 30 at the previously engaged contacts 83 which are separated by the circuit established through the restoring magnet 81 and the battery 11, the bell crank element 82 of the actuated key having previously entered a normally unaligned notch 86 when this notch is brought into alignment with the upper branch of the bell crank lever upon the depression of the key having the notch, the magnet 81 removing the bell crank lever from this notch when this magnet is energized so as to restore the key and permit the contacts 83 to separate. The armature of the magnet 81 is shown as being common to the keys 28 for this purpose. The selection of a busy line extension 25 is further guarded against by the separation of the switch 29 from its normal contact upon the initial operation of the motor magnet 87. Circuit for the motor magnet 87 is traceable

from the grounded battery 48, the interrupter 49, the winding of said motor magnet, the lowermost armature switch of relay 36, the top side of the telephone line extension 25, the topmost waiting contact 26, the upper wiper 27 engaging the same, the wiper 73, the waiting contact 76, to the grounded relay 45 (by way of its upper armature switch) of the calling line. The connection of the wipers 24 and 35 with the selected waiting contacts 23 is had by operations similar to those employed for connecting wipers 27, 30 with the waiting contacts 26 and the magnet 36 operates similarly to magnet 31 for arresting these wipers. The buttons 33 have an association with the ratchet 37 and associating mechanism similar to the association of buttons 28 with the mechanism of ratchet 32 and the wipers 21, 38 are brought into engagement with selected wipers 20 in a manner similar to that employed for connecting the wipers 27, 30 with the contacts 26. The structural mechanism of the keys 28, 33, 12, 13, 14 are similar and similar parts of these keys are given similar characters of reference.

I will now describe the results of the operation of the final key, in this instance key No. 13, as line No. 2 is the called line. From Fig. 5 it will be seen that all the keys employed in extending a telephone line may be depressed simultaneously but that a depressed key 33 cannot come into service until the operations set up by the depressed key 28 have occurred and a depressed key 12, 13, etc., cannot come into service until the operations set up by the depressed key 33 have occurred. It will also be observed that the keys are automatically successively brought into effect, each succeeding key as it is brought into effect being preceded by the restoration of the preceding key. When the depressed key 13 is automatically reached to enable it to take part in the line extending operation the circuit previously partially established at 83 is completed, this circuit being traceable from the upper pole of the battery 11, the lowermost armature switch of relay 63 and its contact, the actuated wiper 55 and its engaged contact 30, the employed waiting contact 78, the actuating wiper 75 engaging the same, the previously closed switch 84, the middle switch of relay 31 and its now engaged contact, the actuated wiper 30 and the contact 26 engaging the same, the switch 29 and its alternate contact, the intermediate armature switch of relay 36 and its engaged contact, the wiper 38 and the contact 20 engaged thereby, the armature switch of relay 16 immediately beneath

the core of this relay and the normal follow-up contact of this armature switch, the lower winding of relay 16, the previously closed contact 83 of the key 13, the employed magnet 81, the relay 68, the series of switches 82 of keys 33, all of which are now in normal position, the magnet 81 pertaining to the keys 33, the series of switches 82 of keys 28, the magnet 81 pertaining to the keys 28, to the lower pole of the battery 11. The relay 16 belonging to the called line is now energized, and a locking circuit for itself is established traceable from the grounded battery 48, the upper winding of relay 16, the armature immediately above the core of relay 16 and its alternate contact, the lower of the two wipers 21 and the waiting contact 20 engaged thereby, the lower of the two wipers 24 and the waiting contact 23 engaged thereby, the lowermost of the two wipers 27 and the waiting contact 26 engaged thereby, the wiper 74 and the contact 77 engaged thereby, both sides of the calling subscriber's line, the calling subscriber's relay 45, to ground. A circuit was previously traced through the relay 68 and this circuit caused this relay to be energized to withdraw its armature and thereby remove ground at this armature from the magnet 50 of the operator selector switch which was actuated as a consequence of the initiation of the connection by the calling subscriber. When this magnet is deenergized the wipers carried by the ratchet wheel 52 are restored to normal whereby the previously selected operator's telephone conductors 64 are subjected to new selection upon the initiation of a new call. When the armature of relay 68 was attracted its nose was disengaged from the notch 67 of the previously depressed key 66 so that the key 66 was automatically restored to normal and in being so restored the switch levers 69 and 70 were separated from their contacts. The associate magnet 63 then has its circuit open at 69 and this magnet 63 is restored to normal and ground connection with the wiper 55 is broken at 70 so that the previously employed operator selector switch may again be employed when another call is initiated. Thus the operator is freed for further selection and the apparatus of keys 28, 33, 12, etc., are restored to normal. The ringing magnet 46 of the called line is consequently energized over a circuit traceable from the grounded battery 48 through the ringing interrupter 88, the uppermost armature switch of the called subscriber's relay 16, and its then engaged contact, the middle switch of called subscriber's relay 45 and its contact, the winding of the called subscriber's ringing relay 46, to ground. This ringing relay is consequently intermittently energized intermittently to include the ringing generator 89 in bridge of the 130

called line by way of the armature switches of the ringing relay 46 and the alternate contact of these armature switches that constitute terminals of said generator. When 5 the called subscriber responds the generator 89 is automatically cut out of circuit during one of the periods in which the actuated ringing relay 46 is deenergized and in which period the called subscriber's telephone is 10 removed from its hook whereby the called subscriber's relay 45 is then energized to open the circuit of the ringing relay 46 to maintain this ringing relay permanently in open circuit during the established connection. 15 The circuit of relay 45 of the called line is traceable from the grounded terminal of this relay 45, both sides of the calling line by way of the released armature switches of ringing relay 46 and their normal contacts, the armature switch of called subscriber's relay 16 immediately above the core of this relay and the alternate contact of this armature switch, the upper coil of this relay 16, to the grounded battery 48, 20 the circuit for the ringing relay 46 being kept open at the middle armature switch of the now energized relay 45. The attracted upper armature switch of relay 45 extends the called line into connection with the conductors leading to the waiting contacts 20 engaged by the wipers 21 so that connection between the calling and called lines is now completed. When the parties are through 25 conversation their relays 45 are deenergized 30 on the restoration of the telephone receivers upon their switch hooks whereby the relays 15, 16, 39, 36, 31 and 71 are included in open circuit so that the armatures of these relays are restored to normal. When the armatures of relays 39, 36, 31 and 71 are restored 35 to normal they disengage the actuating pawls of the associate motor magnets from the ratchet wheels previously operated by these pawls so that these ratchet wheels are 40 restored to normal, as shown in Fig. 6.

Any suitable test feature may be employed. As the system is employed failure of the depressed buttons 12, 13, etc., to restore the normal will indicate to the operator that the desired line is busy and inasmuch as the operator is not released until this button is restored the operator may inform the calling subscriber that the desired line is busy.

Fig. 6 indicates a delaying device by which the ratchet wheel is permitted to restore to normal prior to the return of the actuating pawl of the motor magnet to the position in which it may actuate the ratchet wheel. The delaying detent *a* is pivoted at *b* and is pulled upon by a spring *c* so as to have a position to engage the pawl *d* of the motor magnet when this pawl is raised by the finger *e* operated by the holding magnet 65 when energized. When the holding magnet

is deenergized the finger *f* fixed upon the ratchet wheel strikes the holding pawl *a*, when the ratchet wheel has reached normal, and releases the holding pawl from engagement with the actuated pawl operated by the motor magnet so that this actuated pawl may be restored to its relationship with the ratchet wheel.

In my co-pending application Serial No. 714,417, filed August 10, 1912, I have claimed 75 the key mechanism 28, 33, 12, 13, etc., and I do not limit my present invention to the employment of this key mechanism.

It is desired to make cross reference to my following copending applications: Serial 80 No. 709,405, filed July 15, 1912, Serial No. 709,406, filed July 15, 1912, and Serial No. 709,407, filed July 15, 1912, in which are broadly claimed operator controlled electro-magnetic switches for establishing connection 85 between calling lines and calling line extensions or other telephone lines. By means of one of the systems disclosed in these co-pending applications calling line terminals are moved into connection with contacts of link connectors; in another system direct connection is effected between contacts belonging to calling lines and contacts belonging to called lines; and in the remaining system contacts belonging to link 90 connectors are moved into connection with contacts belonging to the calling lines.

While I have herein shown and particularly described the preferred embodiment of my invention, I do not wish to be limited 100 to the precise details of construction and circuit arrangement shown as change may readily be made without departing from the spirit of my invention.

Having thus described my invention I 105 claim as new and desire to secure by Letters Patent the following:

1. A telephone system including telephone lines extending from stations to an exchange; extensions for such telephone lines 110 having contacts at the exchange; a line extending connecting device for engagement with the contacts; controlling circuits for governing the association of said connecting device, each controlling circuit having a contact for engagement with the connecting device, the controlling circuits being associated with different telephone line extensions; means for changing the character of the controlling circuits; electro-magnetic mechanism in the controlling circuits for maintaining the connecting device in association with a modified controlling circuit; and electro-magnetic switches individual to the controlling circuits for restoring such circuits when their associate line extensions 115 have become connected with telephone lines.

2. A telephone system including telephone lines extending from stations to an exchange; extensions for such telephone lines 120

in the controlling circuits for maintaining the connecting device in association with a modified controlling circuit; and electromagnetic switching mechanism for restoring such circuits when their associate line extensions have become connected with telephone lines.

16. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; electro-magnetic mechanism in the controlling circuits for maintaining the connecting device in association with a modified controlling circuit; and means for restoring such circuits when their associate line extensions have become connected with telephone lines.

17. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means individual to the controlling circuits for changing the character of the controlling circuits; electro-magnetic mechanism in the controlling circuits for maintaining the connecting device in association with a modified controlling circuit; and means for restoring such circuits when their associate line extensions have become connected with telephone lines.

18. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; and electro-magnetic mechanism in the controlling circuits for maintaining the connecting device in association with a modified controlling circuit.

19. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; means for maintaining the connecting device in association with a modified controlling circuit; and electro-magnetic switches individual to the controlling circuits for restoring such circuits when their associate line extensions have become connected with telephone lines. 85

20. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; means for maintaining the connecting device in association with a modified controlling circuit; and means individual to the controlling circuits for restoring such circuits when their associate line extensions have become connected with telephone lines.

21. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; means for maintaining the connecting device in association with a modified controlling circuit; and electro-magnetic switching mechanism for restoring such circuits when their associate line extensions have become connected with telephone lines. 105 110 115 120

22. A telephone system including telephone lines extending from stations to an exchange; extensions for such telephone lines having contacts at the exchange; a line extending connecting device for engagement with the contacts; controlling circuits for governing the association of said con- 125
130

- necting device, each controlling circuit having a contact for engagement with the connecting device, the controlling circuits being associated with different telephone line extensions; operator controlled means for changing the character of the controlling circuits; means for maintaining the connecting device in association with a modified controlling circuit; and means for restoring such circuits when their associate line extensions have become connected with telephone lines.
23. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means individual to the controlling circuits for changing the character of the controlling circuits; means for maintaining the connecting device in association with a modified controlling circuit; and means for restoring such circuits when their associate line extensions have become connected with telephone lines.
24. A telephone system including telephone lines extending from stations to an exchange; extensions for such telephone lines having contacts at the exchange; a line extending connecting device for engagement with the contacts; controlling circuits for governing the association of said connecting device, each controlling circuit having a contact for engagement with the connecting device, the controlling circuits being associated with different telephone line extensions; operator controlled means for changing the character of the controlling circuits; and means for maintaining the connecting device in association with a modified controlling circuit.
25. A telephone system including telephone lines; extensions for such telephone lines; a line extending connecting device for associating a selected telephone line extension with the telephone line having the connecting device; controlling circuits associated with different telephone line extensions for governing the association of said connecting device in determining the extensions of telephone lines; means for changing the character of the controlling circuits; and means for restoring such circuits when their associate line extensions have become connected with telephone lines.
26. A telephone system including telephone lines extending to an exchange; extensions for such telephone lines; a line extending connecting device; controlling cir-

cuits associated with different telephone line extensions for governing the association of said connecting device; and operator controlled means for changing the character of the controlling circuits.

27. A telephone system including telephone lines; extensions for such telephone lines; a line extending connecting device; controlling circuits associated with different telephone line extensions for governing the association of said connecting device; and operator controlled means for changing the character of the controlling circuits.

28. A telephone system including telephone lines; extensions for such telephone lines; a line extending connecting device; controlling circuits associated with different telephone line extensions for governing the association of said connecting device in determining the extensions of telephone lines; means for changing the character of the controlling circuits; means governed by the controlling circuits, when modified, for maintaining the extensions associated therewith in connection with the line extending connecting device; and means for restoring such circuits when their associate line extensions have become connected with telephone lines.

29. A telephone system including telephone lines extending to an exchange; extensions for such telephone lines; a line extending connecting device; controlling circuits associated with different telephone line extensions for governing the association of said connecting device; operator controlled means for changing the character of the controlling circuits; and means governed by the controlling circuits, when modified, for maintaining the extensions associated therewith in connection with the line extending connecting device.

30. A telephone system including telephone lines; extensions for such telephone lines; a line extending connecting device; controlling circuits associated with different telephone line extensions for governing the association of said connecting device; operator controlled means for changing the character of the controlling circuits; and means governed by the controlling circuits, when modified, for maintaining the extensions associated therewith in connection with the line extending connecting device.

31. A telephone system including telephone lines; extensions for such telephone lines; a line extending connecting device; controlling circuits associated with different telephone line extensions for governing the association of said connecting device in determining the extensions of telephone lines and individual to the line extensions pertaining to the line extending connecting device; means for changing the character of the controlling circuits; and means for re-

- storing such circuits when their associate line extensions have become connected with telephone lines.
32. A telephone system including telephone lines extending to an exchange; extensions for such telephone lines; a line extending connecting device; controlling circuits associated with different telephone line extensions for governing the association of 5 said connecting device and individual to the line extensions pertaining to the line extending connecting device; and operator controlled means for changing the character of the controlling circuits.
33. A telephone system including telephone lines; extensions for such telephone lines; a line extending connecting device; controlling circuits associated with different telephone line extensions for governing the 10 association of said connecting device and individual to the line extensions pertaining to the line extending connecting device; and operator controlled means for changing the character of the controlling circuits.
34. A telephone system including telephone lines; extensions for such telephone lines; a line extending connecting device; controlling circuits associated with different telephone line extensions for governing the 15 association of said connecting device in determining the extensions of telephone lines and individual to the line extensions pertaining to the line extending connecting device; means for changing the character of 20 the controlling circuits; means governed by the controlling circuits, when modified for maintaining the extensions associated therewith in connection with the line extending connecting device; and means for restoring 25 such circuits when their associate line extensions have become connected with telephone lines.
35. A telephone system including telephone lines extending to an exchange; extensions for such telephone lines; a line extending connecting device; controlling circuits associated with different telephone line extensions for governing the association of said connecting device and individual to the line extensions pertaining to the line extending connecting device; operator controlled means for changing the character of the controlling circuits; and means governed by the controlling circuits, 30 when modified, for maintaining the extensions associated therewith in connection with the line extending connecting device.
36. A telephone system including telephone lines; extensions for such telephone lines; a line extending connecting device;
- controlling circuits associated with different telephone line extensions for governing the association of said connecting device and individual to the line extensions pertaining to the line extending connecting device; operator controlled means for changing the character of the controlling circuits; and means governed by the controlling circuits, when modified, for maintaining the extensions associated therewith in connection with the line extending connecting device.
37. A telephone exchange system including telephone lines extending from stations to an exchange; extensions for such telephone lines; an electro-magnetic line extending switch having a number of sets of waiting contacts pertaining to different telephone line extensions, and a set of wipers for interchangeable connection with said sets of waiting contacts; electro-magnetic mechanism for holding the wipers in connection with the waiting contacts; and operator governed controlling circuits pertaining to the different telephone line extensions for controlling said electro-magnetic mechanism and having waiting contacts in the sets of waiting contacts to enable the operator to determine the set of waiting contacts to be engaged by the set of wipers.
38. A telephone system including telephone lines; extensions for such telephone lines; an electro-magnetic line extending connecting device; switching mechanism for setting said connecting device into operation and manually modified controlling circuits individual to the different telephone line extensions and each serving, when modified, to stop the moving connecting device in connection with the corresponding telephone line extension.
39. A telephone system including telephone lines; extensions for such telephone lines; an electro-magnetic line extending connecting device; switching mechanism for setting said connecting device into operation; and controlling circuits having operator's means for modifying the same and which are individual to the different telephone line extensions and each serving, when modified, to stop the moving connecting device in connection with the corresponding telephone line extension.

In witness whereof, I hereunto subscribe my name this sixth day of August A. D., 1912.

ELMER R. CORWIN.
